VANITY CHAIR

William T. Harris, Missoula, Mont.

Original application November 7, 1955, Serial No. 38,769,
now Design Patent No. 183,967, dated November 25,
1958. Divided and this application May 21, 1957, Se-
rial No. 46,264

Term of patent 7 years

(Cl. D15—1)

Figure 1 is a perspective view of a vanity chair embodying my new design.

Figure 2 is a front view thereof.

Figure 3 is a side view thereof.

Figure 4 is a plan view thereof.

The characteristic features of my design reside in the portions shown by means of full lines in the drawing.

This is a divisional application of my pending application Serial No. D.38,769, filed November 7, 1955, now Patent No. D.183,967.

I claim:

The ornamental design for a vanity chair, as shown and described.
